UNITED STATES PATENT OFFICE.

WILLIAM E. SNOW, OF HYDE PARK, MASSACHUSETTS, ASSIGNOR TO B. F. STURTEVANT COMPANY, OF BOSTON, MASSACHUSETTS, A CORPORATION OF MASSACHUSETTS.

TURBINE.

No. 891,874.

Specification of Letters Patent.

Patented June 30, 1908.

Application filed November 3, 1906. Serial No. 341,823.

To all whom it may concern:

Be it known that I, WILLIAM E. SNOW, a citizen of the United States, residing at Hyde Park, in the county of Norfolk and State of Massachusetts, have invented certain new and useful Improvements in Turbine-Engines; and I do hereby declare the following to be a full, clear, and exact description of the invention, such as will enable others skilled in the art to which it appertains to make and use the same.

This invention relates particularly to turbines of the type in which the motive fluid is caused to impinge several times against the buckets on the rotating member before being discharged, being reversed in direction after each impact by fixed reversing guides. In turbines of this type it is desirable to afford a path for the motive fluid of substantially unrestricted area, the fluid being constrained only in its direction of travel, so that under all conditions of use it may have a free passage. It is also desirable to reduce as far as practicable the angle through which the motive fluid is turned by the fixed reversing guides, so as to reduce the frictional losses against the guides. Another desideratum is the avoidance of end thrust on the shaft of the turbine.

The object of the present invention is to produce a turbine engine in which the characteristics above pointed out are combined, together with other improvements relating to the admission and exhaust of motive fluid which will be referred to later, and the invention consists in the improved turbine engine hereinafter described, as defined in the claims.

In the drawings, which illustrate the invention more or less diagrammatically, Figure 1 is a side elevation, partly in section, of a turbine engine embodying the present invention; Fig. 2 is a vertical section through the axis of the turbine; Fig. 3 is a horizontal section through the upper portion of the turbine showing in detail the buckets and reversing guides; and Figs. 4 and 5 are diagrammatic representations of the path of movement of the motive fluid, shown in plan and elevation respectively.

The illustrated embodiment of the invention is constructed as follows: The turbine wheel 1, which rotates upon a shaft 2 in the ordinary manner, is provided at its periphery with two rings 3, upon the opposite interior faces of which are formed series of buckets 4 and 5 of the parallel-return type. The turbine is provided with a casing 6 inclosing the wheel, and within the periphery of the casing is mounted a base ring 7 upon which are formed a series of fixed reversing guides 8 which project radially into the space between the buckets 4 and 5. These reversing guides are of such length as to project entirely across the space between the buckets, so as to receive motive fluid from or deliver it to either the tops or bottoms of the buckets. The casing is provided with a series of equally-spaced inlet chambers 9 supplied with motive fluid through a pipe 10 connecting the inlet chambers with a suitable source of supply, and each inlet chamber is connected with an inlet nozzle 11 through which the motive fluid is discharged against the buckets.

As shown in Figs. 1 and 3, the inlet nozzles are inclined so as to direct the motive fluid into the upper ends of one set of buckets, and in order that the impact of the steam may be entirely balanced, so that the wheel may have no unbalanced end thrust upon its shaft, the nozzles are directed alternately in opposite directions, as shown in Fig. 3.

The motive fluid, after entering the buckets from one of the inlet nozzles, follows a course like that shown in Figs. 4 and 5. It first passes from the upper to the lower end of the bucket, thence is discharged against one of the reversing guides near the inner end thereof, and is thus reversed and directed against one of the opposite buckets, then passes to the upper end of such bucket, strikes another reversing guide and is again discharged into a bucket of the first set, and this is repeated until the motive fluid is finally discharged from the wheel through an exhaust deflector 12, which consists of a plate of suitable form, as shown in Figs. 1 and 3, extending between the buckets and directing the motive fluid through an exhaust pas-

sage 13 into one of a series of exhaust chambers 14 interposed between the inlet chambers 9 and connected with an exhaust pipe 15.

The path of movement above ascribed to the motive fluid will be modified according to the speed at which the wheel is rotated, and by other circumstances, so that the number of reversals of the motive fluid may vary, and under certain circumstances 5 motive fluid may flow in both directions over the same reversing guide, being directed in one direction from the bottoms of the buckets on one side and in the opposite direction from the upper ends of the buckets on the 10 other side. This operation may occur, however, without impairing the efficiency of the turbine, since the reversing guides are of sufficient depth to permit the passage of two opposite currents at the same time without 15 interference. Owing to the arrangement of the buckets and the reversing guides, the latter are required to reverse the motive fluid through an angle of substantially less than 180°, thereby securing an economy 20 which is not secured in arrangements in which the reversing guides turn the motive fluid through a greater angle, and the present invention combines with this advantage the repeated action of the motive fluid upon the 25 same set of buckets, being arranged in the illustrated embodiment to receive at least two impacts of the motive fluid against each set of buckets before the motive fluid is exhausted.

30 It is to be noted that the motive fluid, after issuing from the inlet nozzles, has a passage which is entirely unrestricted in area, the stream of motive fluid being confined only in the direction of its travel, so that its path 35 of movement is determined only by its impact against and deflection by the buckets and reversing guides, and it is free to expand in area of cross section as its speed is reduced during its passage through the turbine.

The present invention is the first turbine, so far as the inventor is aware, in which a perfectly balanced action free from end thrust is obtained without the duplication of 40 the operative elements of the machine. It will be noted that the use of two opposite sets of buckets is not in this sense a duplication, since this arrangement is essential to the intended mode of operation of the turbine whether or not the inlet nozzles be arranged to discharge in both directions or 45 only in one direction.

The arrangement of the illustrated embodiment of the invention in which the intermediate reversing guides are mounted upon 50 the fixed member and the parallel-return buckets are mounted upon the moving member is preferred because of the simplicity of construction and the avoidance of high

pressure steam joints, but it is to be understood that, viewed in its broader aspects, the invention contemplates other constructions within the purview of the claims.

The invention is not limited to the details of construction and operation of the illustrated embodiment but may be embodied in other forms broadly defined in the claims.

1. A turbine engine, having, in combination, a wheel and a casing, the one provided with two opposed sets of parallel-return buckets, and the other provided with a set of intermediate reversing guides opposed to and extending across the whole length of the buckets, substantially as described.

2. A turbine engine, having, in combination, a wheel and a casing, the one provided with two opposed sets of parallel-return buckets, and the other with a set of intermediate reversing guides communicating with both the tops and the bottoms of the buckets, substantially as described.

3. A turbine engine, having, in combination, a wheel and a casing, the one being provided with opposed parallel-return buckets, and the other provided with a plurality of sets of intermediate reversing guides, and with inlets and outlets for the motive fluid and exhaust deflectors interposed between the sets of reversing guides to direct the motive fluid outwardly, substantially as described.

4. A turbine engine, having, in combination, a wheel provided with two opposed sets of parallel-return buckets, and a set of intermediate fixed reversing guides extending radially from top to bottom of the buckets so as to afford an unrestricted passage for motive fluid passing from one set of buckets to the other, substantially as described.

5. A turbine engine, having, in combination, a wheel provided with two opposed sets of parallel-return buckets, a set of intermediate fixed reversing guides communicating with both the tops and the bottoms of the buckets, a casing provided with an outlet, and an inlet nozzle located at a distance from the outlet so that the motive fluid operates a plurality of times on one set of buckets before being exhausted, substantially as described.

6. A turbine engine, having, in combination, a wheel provided with opposed parallel-return buckets, a plurality of sets of intermediate fixed reversing guides, a casing provided with peripheral inlets and outlets for motive fluid, and exhaust deflectors interposed between the sets of reversing guides to direct the motive fluid outwardly from the wheel, substantially as described.

7. A turbine engine, having, in combination, a wheel provided with opposed parallel-return buckets, intermediate fixed reversing guides, and inlet nozzles arranged to direct the motive fluid against the opposite sets of

buckets simultaneously so as to balance the end thrust in the wheel, substantially as described.

8. A turbine engine, having, in combination, a wheel provided with opposed parallel-return buckets, a set of intermediate fixed reversing guides, and a plurality of inlet nozzles directed alternately against opposite

sides of the wheel so as to balance the end thrust therein, substantially as described. 10

In testimony whereof I affix my signature, in presence of two witnesses.

WILLIAM E. SNOW.
